UNITED STATES PATENT OFFICE.

EMIL G. JOHANSON, OF CHICAGO, ILLINOIS.

COMPRESSION ROTARY ENGINE.

1,316,957.

Specification of Letters Patent. Patented Sept. 23, 1919.

Application filed March 31, 1916. Serial No. 87,927.

To all whom it may concern:

Be it known that I, EMIL G. JOHANSON, a subject of the King of Sweden, residing at Chicago, in the county of Cook and State 5 of Illinois, have invented certain new and useful Improvements in Compression Rotary Engines, of which the following is a specification.

My invention relates to rotary engines and 10 has particular reference to internal explosion engines.

The object of the invention is to provide an improved compression and explosion engine adapted to accommodate any desired 15 number of cylinders.

With these objects in view my invention consists in the novel construction, combination and arrangement of parts, all as herein-after described in detail, illustrated in the 20 accompanying drawings, and incorporated in the appended claim.

In the drawings—

Figure 1 is a front elevation, partly broken away, of an engine embodying my 25 invention.

Fig. 2 is a section taken substantially on line 2—2 of Fig. 1.

Fig. 3 is a section taken substantially on line 3—3 of Fig. 2.

Fig. 4 is a rear elevation, partly broken away, of said engine.

In the embodiment of my invention herein shown 2 is a base-plate from which rises a pair of posts 3 and 4 on which is mounted 35 a plate 5 which may be of ornamental skeleton form. In the present illustration only a central circular portion is removed and is stamped out to form a rearwardly projecting flange 6 that is connected with 40 a hub 7 by web portions 8, 9 and 10. On the front face of the bearing plate 5 and concentrically with the flange 6, is a band 11 which covers the periphery of a turbine wheel 12 in which is a groove 13 that is 45 open only toward said band 11, as shown in Figs. 1 and 2. The band 11 is secured to the bearing plate 5 by means of bolts 14, which pass through hollow studs 15 on said bearing plate and engage lugs 16 that project 50 from the rear edge of the band 11. These studs are spacers which offset the band 11 from the base-plate the required distance.

The wheel 12 is loosely mounted on a shaft 17 which has its bearings on the hub portion 7. The wheel 12 has a hub portion 18 from which projects a pair of pins or studs

19 and 20 which engage suitable holes in the inner face of a collar 21 that is secured to the shaft 17 by means of set screws 22 and 23, or otherwise. Thus motion is transmitted from the shaft to the wheel 12 through said apertured collar and studs 19 and 20. On the rear end —17'— of the shaft 17 is eccentrically mounted a circular disk 24 which is rotatably mounted in a circular 65 opening 25 in a hub portion 26 of a disk stamped to form said hub 26, as well as a band 27 that is at right angles to said hub and is connected therewith through webs 28, 29 and 30, and a vertical flange 31 out of 70 which portions 32 are stamped to remove superfluous metal. This disk, including the parts 26 to 31, is rotated eccentrically with respect to the shaft 17 by means of the eccentric disk 24 which is held in place in the 75 opening 25 by means of a pair of circular disks 33 and 34 that are a little larger than the disk 24 and thus engage between them the hub portion 26. The disks 24, 33 and 34 may be secured together as by a screw 35 80 which has threaded engagement with a screw hole in the disk 34 that extends through the three disks as shown in Fig. 2.

On the band 11 which covers the periphery of the wheel 12, are a series of tangentially arranged cylinders 36, 37, 38, 39, 40, and 41, the number of which may be varied. Each of these cylinders is mounted in a socket portion 42 of a beveled extension 43 which forms, preferably, an integral part 90 of the band 11 and is provided with a stiffening fin 44. In the band 11 is an opening 45 for each cylinder, through which the explosive mixture is discharged into the groove 13 by means of a piston 46 that is 95 provided with a rod 47 connected through an elbow 48 secured by a screw 49 to the end of the piston rod, and connected by a pivot pin 50 to one end of a pitman 51 pivoted to a wrist-pin 52 on a crank 53. The 100 latter is keyed to a short shaft 54 having bearings in a hub 54 on the rear face of the bearing plate 5. On the shaft 54 is also keyed a crank 56 which is mounted on a wrist-pin 57 secured to the eccentric 105 flange 31.

Near the end 17' of the shaft 17, and adjacent to the disk 34, is a collar 58 that is fast on said shaft. In this collar is a bore 59 that extends from the center to the periphery of said collar and communicates with a short bore 60 in the end 17' of the shaft. 110

The collar 58 is seated in a shallow bore or recess 61 in a hub extension 62 on the hub 7. In the periphery of said extension 62 are a series of six bores 63 that are arranged 5 to register successively with the bore 59 as it is revolved about the axis of the shaft 17. Each bore 63 communicates through a curved pipe or tube with one of the cylinders—36 to 41—these pipes or tubes being designated 10 by the numerals 64 to 69 inclusive. In connection with the cylinders 40 and 41, 70 (Fig. 1) designates the opening into the cylinder from its tube leading from the port 59. The arrangement for each cylinder is 15 the same and its description for one cylinder will therefore suffice for all. The space 71 connected with the cylinder 40, is substantially the explosion chamber in each instance, to be provided with the usual spark 20 plug and sparking mechanism, details not herein shown. Elbow brackets 48' are secured by means of screws 72 and 73 to the plate 5, and on the cylinder wing of each bracket is a flange 74 which encircles the 25 cylinder and is secured thereto in any suitable manner, said cylinder wing being designated by 75 and shown as substantially the head of the cylinder. On the port end 17' of the shaft 17, and against the disk 33, 30 is shrunk a collar 76. Opposite the hub 62, and secured to the opposite side of the bearing plate 5, is a hub 77 which serves as an additional bearing support for the shaft 17.

The exhaust port is simply a bore 78, intersecting the rear end —83— of the groove 13. 82 is the forward end of this groove which serves to receive the driving force. The reaction is against the piston head the inward stroke of which extends to the bottom of the groove, trough or channel 13. For this purpose the piston head has a movable portion 79 from which at right angles extends a part 80 through which the rod 40 of the piston passes and which lies against 45 the back of the piston head, as shown in the sectioned cylinders 40 and 41 in Fig. 1.

The part 80 is held normally against the piston-head by a spring 81 between the outer end of the piston and said part 80. The spring 81 actuates the piston-extension 50 79—80 the moment the abutment —82— has traveled by the part 79.

The operation is as follows: The engine having been started with parts in positions shown in Fig. 1 the compressed gases in 55 front of the piston will be exploded against the abutment or end 82 and against the walls of the explosion chamber and against the piston and piston extension. The abutment 82 being forced past the piston extension 79 60 60 the spring 80 will snap the extension 79—80 to form a dividing wall in the groove. The return or upward movement of the piston permits the exploded gases in the rear of the piston extension 79 to escape toward the 65 outlet 78. By the time the end 83 of the groove reaches the extension 79 said extension will have been fully withdrawn from 70 out of the groove and will rest against the periphery of the wheel during the compression, or downward, stroke until the end or abutment 82 passes it.

I claim as my invention:—

The combination with a turbine wheel having a groove in its periphery one end 75 of which forms an abutment, and having at the opposite end of said groove an exhaust port, of an encircling band which closes said groove on the periphery of said wheel, a series of cylinders mounted on said band, 80 pistons in said cylinders which compress explosive mixture against said wheel and into said groove, movable heads on said pistons arranged to move into said groove independently of the movements of said 85 pistons, means for exploding gases between said abutment and each of said heads and pistons, and an eccentrically rotatable disk connected with and actuating said pistons.

In testimony whereof I have hereunto 90 signed my name.

EMIL G. JOHANSON.
